[57] CLAIM

The ornamental design for a table leg support, as shown and described.

DESCRIPTION

FIG. 1 is a perspective view of a table leg support, showing my new design; the broken lines are for environmental purposes only and form no part of the claimed design.

FIG. 2 is a side elevational view of the ornamental table support shown in FIG. 1, as viewed along one of the feet of the support. The side view is similar when viewed from any of the other feet of the ornamental table support.

FIG. 3 is a top elevational view of the ornamental table support shown in FIG. 1.

FIG. 4 is a bottom elevational view of the ornamental table support shown in FIG. 1; and,

FIG. 5 is an enlarged partial view of the central mesh feature of the ornamental leg support shown in FIG. 1.
